UNITED STATES PATENT OFFICE.

WALTER R. BALDWIN, OF BEREAL, OHIO.

BUSINESS-REGISTER.

1,246,843.

Specification of Letters Patent. Patented Nov. 20, 1917.

Application filed February 26, 1912. Serial No. 679,809.

To all whom it may concern:

Be it known that I, WALTER R. BALDWIN, a citizen of the United States, resident of Berea, county of Cuyahoga, and State of Ohio, have invented a new and useful Improvement in Business-Registers, of which the following is a specification, the principle of the invention being herein explained and the best mode in which I have contemplated applying that principle, so as to distinguish it from other inventions.

My invention relates to a form of account book, or business register, whereby a system of book-keeping may be practised, such as will permit of a ready and accurate determination of the condition of the business at the ends of specified succeeding periods of time.

The object of my said invention is to so arrange such register that an inspection of the books will enable the examiner thereof or the book-keeper to determine at a glance, the total amount and distribution of receipts, the total amount of and distribution of disbursements, for a given specified period of time, as well as other data.

The said invention consists of means hereinafter fully described and particularly pointed out in the claims.

The annexed drawing and the following description set forth in detail one mode of carrying out my invention, the disclosed means, however constituting but one of various mechanical forms in which the principle of my invention may be applied.

In said annexed drawing:

Figure 1 represents a perspective view of a register embodying my invention.

Fig. 2 represents a plan of one of the two differently arranged sheets provided in said register.

In that form of my invention, of which the drawing is an illustration, I bind together a series of alternately occurring differently arranged sheets A and B, a sheet A occurring first in the register. Each of these sheets is provided with rulings, a and b , forming parallel columns, a' and b' , and rulings, a^2 and b^2 , at right-angles to the latter, forming parallel spaces, a^3 and b^3 . All but two of columns a' , are provided with headings designating the various accounts which may be debited with receipts, as shown, and the last column is provided with a heading designating that the spaces therein are for the receipt of figures indicating the balance of cash on hand at the beginning of each day's business. In addition, another heading is provided, as shown, indicating that the spaces in the corresponding column, are for the reception of figures indicating the amounts paid out by check during each of such specified periods. In addition to the column for the reception of the figures indicating the amounts paid out by check, there is also a column with suitable heading indicating the amount of cash to start with at the beginning of each period, together with a column with suitable heading for the balance of cash at the beginning of each period.

All but two of columns b' are provided with headings designating disbursements, as shown, and the last column is provided with a heading designating that the spaces therein are for the receipt of figures indicating the balance of cash on hand at the end of each day's business. An additional column and suitable heading therefor is provided on this sheet for indicating the deposits in bank.

Sheet A will therefore show all the receipts, balance at the beginning of the day's business, and the distribution of such receipts, and the sum of the figures in a given space a^3 will balance the sum of the figures in a corresponding space b^3 . Sheet B will similarly show all the disbursements, balance at the end of the day's business, and the distribution of such disbursements.

Each sheet may be provided at its left with a column of succeeding dates in the spaces a^3 and b^3 , and at the right with a column and heading for the final daily balances. I prefer, however, inasmuch as these dates and balances are the same for any given day, to cut away sheets A at their two lateral edge portions so as to expose these last two-named columns, as shown in Fig. 1. By this means a single date entry and a single balance entry will answer for both sheets, as will be readily understood.

If convenient and in order to have the amounts charged on accounts always ready for inspection, I prefer to provide a column on sheet B and at the left for these amounts. In order that the balance may not be disturbed of course these items of charged accounts would have to appear on each sheet. In order to prevent the necessity for writing these items twice I prefer to cut away sheet A so as to expose this column also.

In order to show the true condition of the business, I have also provided a column next to the date column for showing the amounts charged. As these amounts do not enter into the matter of determination of cash on hand, they are shown on both sheets, and preferably by still further cutting away sheets A, so that a single entry on sheet B will suffice for both sheets, as shown.

10 In order that the general balances shown on the extended portion of each of the adjacent sheets B, may be identified with the figures covering the proper periods of time, those spaces on the two sheets which are

15 designed to receive the figures relating to the same periods of time, are caused to accurately register to each other. In this manner the general balance may be identified with the proper distributions and other accounts shown on the two sheets.

It will therefore be noted that sheet A contains all the items which may be designated as receipts, plus the amount of checks paid out, the amount of cash to start with and the balance of cash at the beginning of the business period. Sheet B contains all of the items which may be classed as expenditures with the addition of the deposits in bank and the balance of cash on hand at the close of the business period.

It will therefore be seen that a novel grouping of items is adopted which enables me to obtain the balances in a ready and simple manner. This arrangement therefore permits me to keep a record of final entry which will give at a glance the condition of all of the details of the business. The arrangement furthermore permits me to readily check and discover errors. The sum of all the items in any horizontal space on sheet A must be equal to the sum of the items in the horizontal space on sheet B, so as to give the same balance in both cases. If these two sums are not equal to each other, an error is apparent and can be readily detected. If the items in the various spaces are correct and the two sums do not balance, then the error is evidently in one of the sums in either one of the spaces and can be readily checked, or the error is merely one of addition. Assuming now that at the

end of the week's business a balance is struck and it is found that the two sums do not agree and it is also found that there is no error of addition in one of the week's totals, then the error must be in adding up one of the vertical columns. One of the totals would therefore be incorrect. In this event all that it is necessary to do is to add up the various vertical columns to see whether or not their totals are correct and the error will thus be discovered.

Having thus fully described my invention, what I claim and desire to secure by Letters Patent is:

1. In a business register, the combination with a sheet provided with rulings forming parallel columns, rulings at right angles to the latter forming parallel spaces, headings for certain of said columns designating various classes of receipts, a heading designating the balance on hand at the beginning of a specific period of time, another heading for a column for receiving the amount of checks paid out and a third heading for a column providing for the entry of the amount of cash to start with; of a second sheet similarly ruled, provided with headings designating the various expenditures, together with a heading and column therefor indicating the balance on hand at the end of such specific period of time, and a heading indicating the amount of deposits in the bank, the side edges of the first mentioned sheet being cut away to permit certain columns and spaces of the second sheet to be readily observed.

2. In a business register the combination of a sheet provided with suitable columns, said columns having headings indicating each day's receipts, cash on hand at the beginning of each day's business, and checks paid out during each day, and a second sheet having columns indicating each day's disbursements and cash on hand at close of each day's business.

Signed by me, this 15 day of February, 1912.

WALTER R. BALDWIN.
